Attorney.

UNITED STATES PATENT OFFICE.

FREDERIC L. WANKLYN, OF MONTREAL, QUEBEC, CANADA.

RAILWAY SIGNAL-FUSEE.

1,381,371.

Specification of Letters Patent. Patented June 14, 1921.

Application filed September 1, 1920. Serial No. 407,558.

To all whom it may concern:

Be it known that I, FREDERIC L. WANKLYN, a subject of the King of Great Britain, and resident of the city of Montreal, Province of Quebec, Dominion of Canada, have invented certain new and useful Improvements in Railway Signal-Fusees; and I do hereby declare that the following is a full, clear, and exact description thereof.

10 My invention relates to railway signal fusees disclosed in my pending application Serial No. 367,019 for use particularly in railway signaling and adapted to be effective during the day as well as during the 15 night by having combined therein smoke-producing and light-producing elements.

Some difficulty has been experienced in providing a fusee the dimensions of which conform to the requirements of the railway commissions and in which the smoke signal will be of a duration equal to that of the light signal and it is the object of the present invention to overcome this difficulty by providing a railway signal fusee 25 of standard dimensions and constructed and arranged to produce a continuous flare or light signal and a series of successive smoke signals the latter covering a length of time equal the duration of the light signal.

30 To this end my invention consists of the particular construction and arrangement of parts hereinafter described and pointed out in the drawing.

For full comprehension, however, of my 35 invention reference must be had to the accompanying drawings in which—

Figure 1 is a side elevation partly in vertical section of a fusee constructed according to my invention;

40 Fig. 2 is a transverse sectional view taken on line 2—2 Fig. 1; and

Fig. 3 is a similar view to Fig. 1 illustrating a modification.

45 My improved fusee consists of a tubular container 2 divided longitudinally by a partition 3 of ogee curvature in cross section, the latter constituting an integral part of the container which is constructed of an inflammable material such as paper or the like. The lower end of the tubular container is closed by a relatively heavy head 4 carrying the usual spike 5 while the opposite end of the container is adapted to be protected by a cap 6, the latter being 50 provided with the usual igniting substance 7 protected by a tape 8 which also serves to

seal the cap thereon. One of the chambers of the container is completely filled with any well known light-producing mixture indicated at 9 while the other chamber is 60 filled with a series of smoke producing pellets 10 and non-inflammable fillers 12, the latter filling the spaces between the pellets which are uniformly distributed throughout the length of the fusee.

65 In order to successively ignite the pellets from the light-producing mixture, the opposite ends of a slow match 13 are respectively connected to the light-producing mixture and to each of the smoke producing 70 pellets so that as the former burns the slow matches will be successively ignited and in turn will ignite their respective pellets.

If desired my invention may be embodied in the construction illustrated in Fig. 3. 75 In this embodiment the tubular container is not divided longitudinally into separate chambers, the pellets being embedded directly in the light-producing mixture.

It may be found desirable to provide each 80 pellet with vertical perforations to promote combustion.

From the foregoing description it will be seen that the fusee is provided of uniform diameter throughout and in which an intermittent smoke signal will be produced 85 covering a period of time equal to the duration of light signal.

What I claim is as follows:

1. A railway signal fusee containing a 90 light producing element extending throughout the length of the fusee and constructed and arranged to burn continuously and a series of smoke producing elements distributed throughout the length of the fusee. 95

2. A railway signal fusee containing a light producing element extending throughout the length of the fusee and constructed and arranged to burn continuously and a series of smoke producing elements distributed throughout the length of the fusee and constructed and arranged to be successively ignited as the light producing element burns, and means in contact with said light producing element and with each of 100 said smoke producing elements and constructed and arranged to ignite the latter from the former.

3. A railway signal fusee divided longitudinally into two chambers one of said chambers containing a light producing element 110 constructed and arranged to burn continu-

ously, the other chamber containing a series of smoke producing elements, and non-inflammable means spacing said smoke producing elements apart, said smoke producing elements being constructed and arranged to be successively ignited as the light producing element burns.

4. A railway signal fusee consisting of a tubular container divided longitudinally throughout its length into two chambers and having one end closed, a light producing element within one of said chambers and completely filling the same, a series of smoke producing elements located within the other of said chambers and uniformly spaced apart throughout the length of the same, a non-inflammable substance filling each of the spaces between the smoke producing ele-

ments, an ignition device effecting communication between each of said smoke producing elements and the light producing element whereby the smoke producing elements are ignited as the light producing element burns, and a cap protecting one end of said fusee.

5. In a railway signal fusee, light-producing means adapted to burn continuously and smoke-producing means adapted to burn intermittently.

In testimony whereof I have signed my name to this specification in the presence of two witnesses.

FREDERIC L. WANKLYN.

Witnesses:

GORDON G. COOKE,

WILLIAM J. C. HEWETSON.
